PROCESS FOR CLEANING COPPER-CONTAINING METAL ARTICLES

Joseph J. Bayer, Blackwood, N. J.

No Drawing. Application September 17, 1947,
Serial No. 774,690

7 Claims. (Cl. 134—20)

(Granted under the act of March 3, 1883, as amended April 30, 1928; 370 O. G. 757)

1

The present invention concerns a process for cleaning a copper-containing metal article and in particular concerns a process which includes both heat and chemical treatment of the copper-containing article.

In welding with an acetylene torch the burner tip of the torch becomes corroded with use and it is necessary either that the burner tip be discarded or reconditioned by cleaning. The corrosive material formed on the burner tip largely comprises carbon and also oxides and other compounds of the metal from which the burner tip is fabricated. Thus burner tips, which are formed of a copper-containing material, such as brass, become corroded in the use by the formation of carbon and of oxides of copper, such as cuprous oxide and cupric oxide.

Because of the chemical and physical characteristics of the corrosive material and because of the high temperatures under which such corrosive material forms on the burner tip, there is a strong bond between the corrosive material and the metal of the burner tip. For this reason it is difficult and often impossible to remove such corrosive material by a simple wiping operation.

Formerly it has been customary to clean such corrosive material from the metal burner tip by an initial hand operation using emery cloth and by a final machining operation on a lathe to produce a polished surface. Also it has been customary to dress the ends of the tips by filing. This method of cleaning the corrosive material from the metal burner tips has the disadvantage of being inordinately time consuming. A further disadvantage resides in the fact that there is a tendency to chip and nick the burner tip with the result that the tips are rendered defective and dangerous to use.

The present invention overcomes these disadvantages by providing a cleaning process that does not involve the use of abrasive material and does not necessitate a machining operation. This process embodies the steps of initially heating the burner tip to a relatively high temperature followed by quenching the burner tip for a few seconds in a solution of zinc chloride followed by a final quenching in a water bath until the burner tip is cooled.

An object of the invention is to provide a process for cleaning a copper-containing metal article by heating the article and quenching the article in a zinc chloride solution.

Another object is to provide a process for cleaning a copper-containing metal article by heating the article and quenching the article in a solution

of zinc chloride and ammonium chloride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc chloride and ammonium chlo-

ride.

Still another object is to provide a process for

cleaning a copper-containing metal article by

heating the article and quenching the article in

a solution of zinc

metal article comprising the steps of heating the article and quenching the article in a zinc chloride solution.

2. A process for cleaning a copper-containing metal article comprising the steps of heating the article to a temperature of about 900° F., and quenching the article in a zinc chloride solution.

3. A process for cleaning a copper-containing metal article comprising the steps of heating the article, quenching the article in a zinc chloride solution for a few seconds, followed immediately by quenching the article in a water bath until cool.

4. A process for cleaning a copper-containing metal article comprising the steps of heating the article and quenching the article in a solution comprising zinc chloride as a principal ingredient.

5. A process for cleaning a copper-containing metal article comprising the steps of heating the article and quenching the article in a solution comprising zinc chloride and ammonium chloride.

6. A process for cleaning a copper-containing metal article comprising the steps of heating the 25

article and quenching the article in a solution comprising about one gallon of water solvent and about one pound of solute including about 93% by weight of zinc chloride and about 7% by weight of ammonium chloride.

7. A process for cleaning a copper-containing metal article comprising the steps of heating the article to a temperature of about 900° F., quenching the article for a few seconds in a solution comprising about one gallon of water solvent and about one pound of solute including about 93% by weight of zinc chloride and about 7% by weight of ammonium chloride, followed immediately by quenching the article in a water bath until cool.
